UNITED STATES PATENT OFFICE.

ARTHUR J. ADAMS, OF CHICAGO, ILLINOIS, ASSIGNOR TO FULTON MANUFACTURING COMPANY, OF CHICAGO, ILLINOIS, A CORPORATION OF ILLINOIS.

PERAMBULATOR, GO-CART, &c.

1,111,516.

Specification of Letters Patent.

Patented Sept. 22, 1914.

Application filed March 1, 1913. Serial No. 751,422.

To all whom it may concern:

Be it known that I, ARTHUR J. ADAMS, a citizen of the United States, residing at Chicago, in the county of Cook and State of Illinois, have invented a new and useful Improvement in Perambulators, Go-Carts, &c., of which the following is a specification.

This invention relates particularly to an improved foot-support adapted for use in connection with baby-carriages, go-carts, etc.

The primary object of the invention is to provide an improved and simplified adjustable foot-rest which can be manipulated in an improved manner, and which possesses certain advantages in construction and use.

The invention is illustrated in its preferred embodiment in the accompanying drawings, in which—

Figure 1 is a broken elevational view, showing the front portion of a perambulator constructed in accordance with my invention; Fig. 2, a broken plan sectional view of same, taken as illustrated at line 2 of Fig. 1; Fig. 3, a broken sectional view taken as indicated at line 3 of Fig. 2; and Fig. 4, a broken sectional view taken as indicated at line 4 of Fig. 3.

In the illustration given, A represents the running-gear frame of a perambulator of the folding type equipped with wheel-forks A¹ connected in the usual way, by pivots 1, to brackets 2 with which the running-gear frame is equipped; B, the seat mounted on the frame through the medium of springs 3 in a well-understood manner; C, the foldable arms of the superstructure; and D, the improved adjustable foot-rest.

The running-gear frame A preferably comprises the usual tubular side members 4; and the foot-rest D has a frame member of general U-form and composed of side members 4^a and a cross member 4^b. The side members 4^a are curved vertically, so that the front piece 4^b is normally elevated somewhat above the plane of the running-gear frame, while the rear ends of the members 4^a are disposed in the plane of the running-gear frame, as illustrated in Fig. 3. The frame member of the foot-rest constitutes a tubular member; and the rear ends of the members 4^a are separated from the front ends of the members 4 by the space 4^c.

Secured to the rear end portions of the members 4^a, by rivets 5, are connecting members 6 which may be stamped from sheet-

metal. These members have part-cylindrical upper portions 6^a and down-turned flanges 6^b. The rear end portions of the members 6 embrace the front end portions of the members 4, and the rear extremities 60 of the members 6 are connected, by pivots 7, to the side-members 4 of the running-gear frame in the rear of the front wheel-brackets 2. The inner flanges 6^b are cut away, as indicated at 6^c, to accommodate the rearwardly turned ends 8 of a front cross member 8^a of the running-gear frame.

Secured to the front flanges of the front wheel-brackets 2 are bracket members, or locking members, 9. These brackets are secured by rivets 10 and have lower portions provided with locking-perforations 11. The upper portions of the members 9 are bent forwardly to lie below the front portions of the members 4, where they are secured by 70 rivets 12. The extremities of the members 9 are bent upwardly to engage the front ends of the members 4, and are provided with locking-perforations 13.

In the spaces 4^c are pivots 14 which connect the flanges 6^b. The pivots 14 support angular levers 15 which have down-turned arms 15^a equipped with locking-studs 15^b, and which have arms 15^c equipped with springs 15^d, which bear on the rear end portions of the members 4^a. To provide bearings on the pivots 14, the central portions of the levers 15 are struck upwardly, as indicated at 15^e, and below the pivots the folded portions of each lever are connected by a 85 rivet 16, which thus prevents dislodgment of the lever.

The foot-support D has a pouch 17, the front upper portion of which is connected, at 17^a, with a cross member 4^b, while the rear 95 end of the pouch is connected, at 17^b, to the front portion of the seat. Supported on the bottom member 18 of the pouch is the usual foot-board 18^a.

In the position shown in Figs. 2 and 3, the locking-stud 15^b of the lever 15 engages the lower locking-shoulder or perforation 11. In this position, the members 4^a constitute virtual extensions of the side members 4 of the running-gear frame. When 105 desired, the levers 15 may be operated against the force of their springs to release the foot-rest from the locked position shown in Fig. 3, and when the foot-rest is swung up to the position shown in Fig. 1 the 110

locking-studs 15^b will automatically engage the perforations 13. When the foot-rest is lowered, the locking-studs will automatically engage the perforations 11.

5 From the foregoing description, it will be understood that the frame of the foot-rest constitutes virtually a swinging extension of the running-gear frame; and this swinging extension is capable of becoming 10 automatically locked in either the lowered or the raised position, being releasable at will, however, to permit adjustment.

The foregoing detailed description has been given for clearness of understanding 15 only, and no unnecessary limitations should be understood therefrom, and the appended claims should be construed as broadly as permissible in view of the prior art.

What I record as new and desire to secure 20 by Letters Patent, is:—

1. In a perambulator, the combination of a running-gear frame comprising side members, and a foot-rest comprising side members adapted to form virtual extensions of 25 said first-named side members, said second-named side members equipped with connecting members pivotally joined to the first-named side members in the rear of the front ends thereof, and fitting over the 30 top front end of said first named side members to hold said second named side members in normal lowered position, and means for securing said foot-rest in the elevated position.

35 2. In a perambulator, the combination with the running-gear frame, of a front extension therefor pivotally connected therewith, locking members carried by the front portions of said running-gear frame and 40 each equipped with a lower perforation and an upper perforation, and locking levers carried by said front extension and equipped with studs adapted to engage said perforations.

45 3. In a perambulator, the combination

with the running-gear frame, of a front extension therefor comprising a general U-shaped member having side arms with their rear ends lying in the plane of the side members of the running-gear frame, 50 members embracing said side-arms and rigidly secured thereto, and embracing also the front portions of the side members of the running-gear frame and pivotally connected therewith, a pouch connected with said front extension, and means for locking said front extension in the elevated position.

4. In a perambulator, the combination with the running-gear frame of a front extension therefor pivotally connected therewith, a pouch connected with said front extension, spring-actuated locking levers mounted on said front extension, and means carried by the front portions of the side members of the running-gear frame and 65 co-acting with said locking levers when the front extension is in either the elevated or the lowered position.

5. In a perambulator, the combination of a running-gear frame, arms of U-shaped 70 cross-section having their rear ends pivotally connected with the side members of said running-gear frame and having their front ends projecting past the front ends of the side members of the running-gear 75 frame, a frame-member having arms received in the front portions of said first-named arms and rigidly secured thereto, spring-held locking levers having their central portions pivoted in said first-named 80 arms, said levers having downwardly extending arms equipped with locking-studs, and locking means carried by the front portions of the side members of the running-gear frame and co-acting with said locking- 85 studs.

ARTHUR J. ADAMS.

In presence of—

J. G. ANDERSON,
L. HEISLAR.
